UNITED STATES PATENT OFFICE.

ENGLAND J. BARKER, OF MORGAN PARK, ILLINOIS.

AUTOGRAPHIC REGISTER.

1,033,146.

Specification of Letters Patent. Patented July 23, 1912.

Application filed April 22, 1907. Serial No. 369,599.

To all whom it may concern:

Be it known that I, ENGLAND J. BARKER, a citizen of the United States, and a resident of Morgan Park, in the county of Cook and 5 State of Illinois, have invented certain new and useful Improvements in Autographic Registers, of which the following is a clear, full, and exact description.

My invention relates to autographic registers, and particularly to that kind known 10 as "tripligraphs", and similar in principle to that for which Letters Patent of the United States were granted to me, May 31, 1904, No. 761,436.

15 The object of my invention is to accomplish the same results as I accomplished by the autographic register covered by said patent, namely, to enable the same to be used either for a register in which one of the record-strips is rewound within it, or a register in which the rewinding feature is dispensed with, and from which two or more or all of the record strips issue so that they can be conveniently torn off.

25 A further object of my invention is to permit this to be done without necessitating the removal of the actuating crank from the extended end of one shaft to that of another. And it is also an object of my invention to 30 employ gearing to accomplish this result simply by the displacement of a single gear, substantially as hereinafter fully described and as particularly pointed out in the claims.

In the drawings: Figure 1 is a side elevation of the end of an autographic register to which my improvements are applied, broken away from the remainder of the machine, and with the guard-plate removed. Fig. 2 is a plan view of the same, with said 40 guard-plate restored to its proper position. Fig. 3 is a side view of the train of gearing constituting my invention, separated from the machine, and showing the adjustable shifting gear in position to transmit motion 45 from the drive-gear to the delivery rollers. Fig. 4 is a vertical transverse section taken on dotted line 4, 4, Fig. 3. Fig. 5 is a plan view of a modified form attached to a broken away portion of the case of said register. Fig. 6 is a view similar to that shown in Fig. 3, showing a modified form of my invention. Fig. 7, is a longitudinal sectional view of a detail of the invention 50 shown in Fig. 5. Fig. 8, is a fragmental view, showing the pawl and ratchet mechanism employed in my invention.

My invention is applied to the hinged or movable section B of the casing of an autographic register of the kind shown and described in the aforesaid Patent, 761,436, and its purpose is not to change but to facilitate the operation of the machine. In this machine the strips of record paper are usually unwound from rolls which are removably journaled in the stationary section of the casing (not shown) and in like manner in the hinged section B thereof. These strips of paper are directed to the rear end of the bed-plate b or table, and are then passed forward over the same, where they can be written upon if desired. At the forward end of the bed-plate are two delivery rollers c, d, the journals of the shaft of the lower one of which have bearings in the side-walls of the hinged section B, and the journals of the upper one of which have bearings in the ends of rocking-frames D which, intermediate their ends, are securely mounted on the ends of a rock-shaft D', that has bearings in the side-walls of the register. The rocking-frames can be moved, when desired, so as to lift the upper delivery roller c from the lower, d, near the front end, and suitable bearings are provided in the side-walls of the hinged section for the journals of a removable take-up or record receiving roller H, one of which extends through its bearings, and has a suitable gear 2 secured to it, outside of but adjacent to the side-wall of the machine.

I do not claim any invention in so much of the autographic register as I have thus far described, because my invention is designed principally for the purpose of being able to actuate the delivery-rollers directly 95 through the medium of the record-strip wound on the take-up roller H or independently thereof through the medium of the drive-gear and an idle-gear adapted to be thrown into mesh therewith and the gears 100 on the delivery-rollers, according as may be desired. The uppermost record strips of paper pass out of the register immediately in front of the rollers c, d, and can be torn off, but the undermost strip of record paper 105 extends between the delivery rollers c, d, down to the record roller H, upon which it is wound. When, however, the device is to be operated directly by the delivery-rollers, the strip of paper leading to the take-up 110 roller H is severed and thus disconnected from said roller, leaving the strips of paper

passing over the platen to be drawn out by the delivery-rollers *c* and *d*, as will be understood. Contiguous to the inside of their bearings the delivery rollers *c*, *d*, are provided with intermeshing gears *c'*, *d'*, so as to make them revolve at the same speed, and the journal of the lower delivery roller, upon which gear *d* is mounted, is extended through its bearings and has a gear *S* secured thereto.

At a point between gear 2 on the extended end of the journal of the record roller and gear *S* I provide bearings in the sides of section B for a shaft 5, which latter has one end extended through its bearings and has a gear 6 mounted thereon, and beyond said gear has a suitable crank 20 suitably secured thereto. On the opposite end of shaft 5 next the inner surface of the side-wall of the register, a ratchet 7 is mounted which is engaged by a pawl 8 pivoted to the side-wall and prevents the shaft 5 from reversing. Gear 6 engages a comparatively large idle-gear 9, which latter is journaled on a stud 10 projecting outwardly from the side-wall of the register, and this idle-gear 9 meshes with the gear 2 of the record-roller.

A guard 12 consisting of a suitably shaped plate is secured in front of the side-wall by means of screws and spacing washers, to protect and guard the train of gears hereinbefore mentioned, and this guard 12 is provided with openings for the adjacent extended ends of the shaft 5 and the journals of the record roller to pass through. At a suitable point between gears 6 and *S*, a slot 13 is made in said shield, which is elongated in a direction intersecting an imaginary line connecting the axes of shaft 5 and roller *d* at an angle of, say, about ninety degrees. A spindle 14 extends transversely through slot 13 and its inner end terminates between plate 12 and the adjacent side of the register, and the outer portion of spindle 14 extending through slot 13. Said outer portion is screw-threaded and provided with a thumb-nut 15. On the inner end of spindle 14 an idle gear 16 is journaled, which, when the spindle 14 is moved to the lower limit of slot 13, will be out of engagement with gears 6 and *S*, but which, when the spindle is moved a sufficient distance toward the upper end of slot 13, will intermesh with said gears *S* and 6 and transmit the motion of the latter to the former. In order to retain idle-gear 16 either in or out of engagement with gears 6 and *S*, a nut 15 is tightened to clamp the spindle in the desired position.

In Figs. 5, 6 and 7 of the drawings, I show a modified form of my invention. This consists in providing an idle-gear 18, which, in one position, will be in engagement with a drive-gear 17, and in its other

position will be thrown out of engagement with the drive-gear 17, and into engagement with the gear 19 on the extended end of one of the gripping-rollers. When out of engagement with the gripping-roller gear 19 the drive-gear imparts motion to the take-up or record-roller through the medium of a large idle-gear 20', which meshes with a gear 21 fast on the adjacent end of the extended journal of said take-up roller. In order to accomplish this result I extend the end of the shaft or stud 22 on which gear 18 is journaled beyond the outer face of the latter, and feather said gear on said extended end (in any well-known manner) so that the gear will have a longitudinal movement thereon but will revolve therewith. I provide this gear 18 with an outwardly extended boss, 23, and keep the same normally at the limit of its movement toward the adjacent side of the register by means of a coil expansion-spring 24 which is interposed between the outer headed end of shaft 22 and said boss. When the boss 23 is at the limit of its movement toward said register the drive-gear 17 is engaged by the idle gear 18 and actuates the gripping rollers as well as the take up or record roller 21, and the gear 18 will be kept in engagement with the drive-gear 17 by the expansion-spring 24. When, however, the gear 18 is moved to the outer limit of its movement on shaft 22 to disengage the same from the drive-gear, said gear 18 is retained at the outer limit of its movement by a spring depressed bolt 26 seated in the outer end of the boss 23, which enters a circumferential groove 27 made in shaft 22 with reference to the same. In order to operate gear 17 a handle 25 is secured to the outer end of the shaft 28 at such a distance from the side of the register as not to interfere with the shaft 22.

What I claim as new is:—

1. In an autographic register the combination with the gripping-rollers and the take-up roller, pinions on the ends of the journals of said gripping rollers that mesh with each other, of a drive-gear located between said gripping rollers and the take-up roller, and separate gearing connecting said drive-gear with the take-up roller gear including a single idle pinion connecting said drive-gear and gripping-roller gear and adapted with its axis to be moved transversely to the longitudinal direction of the axis in and out of mesh with said gearing and independent of the other gears comprising said gearing.

2. In an autographic register the combination with the gripping-rollers and the take-up roller having journals on their outer ends gears on the ends of said journals, of a drive-gear located between said gripping-rollers and the take-up roller, gearing con-

necting said drive-gear with the take-up roller gear, and a shield secured in front of said gear having a slot therein between the drive-gear and the gripping roller gear, a transverse spindle extending through and adjustable in said slot having its outer end screw-threaded, a nut on the outer end of said spindle, and an idle-gear journaled on the inner end thereof adapted to be moved independently into and out of mesh with one of said gears.

3. In an autographic register the combination with the gripping-rollers and a removable take-up roller having journals on their outer ends gears on the ends of said journals, of a drive-gear located between said gripping-rollers and the take-up roller, gearing connecting said drive-gear with the take-up roller-gear, and a shield secured in front of said gear having a slot therein between the drive-gear and the gear on the end of one of said gripping rollers, a transverse spindle extending through and adjustable in said slot having its outer end screw-threaded, a nut on the outer end of said spindle, and an idle-gear journaled on the

inner end thereof adapted to be moved independently into and out of mesh with one of said gears.

4. In an autographic register the combination with the gripping-rollers and the take-up roller pinions on the ends of the journals of said gripping rollers that mesh with each other, of a drive-gear mounted between said gripping-rollers and the take-up roller, separate gearing connecting said drive-gear with the take-up roller gear, a plate fitted over the front of said gears and pinions having a slot adjacent said gripping-rollers, and an idle pinion adapted to be moved bodily into and out of mesh with said gripping roller gear, and the journal of which is adjustable in said slot, substantially as described.

In testimony whereof I have hereunto set my hand and seal this 15th day of April, A. D., 1907.
